UNITED STATES PATENT OFFICE.

WALTER E. BUCKINGHAM, OF BROOKLYN, NEW YORK, ASSIGNOR TO LACKAWANNA STEEL COMPANY, OF NEW YORK, N. Y.

JUNCTION MEMBER FOR STEEL SHEET-PILING.

1,032,109.

Specification of Letters Patent. Patented July 9, 1912.

Application filed November 1, 1910. Serial No. 590,101.

To all whom it may concern:

Be it known that I, WALTER E. BUCKINGHAM, a citizen of the United States, residing at Brooklyn, in the county of Kings and State of New York, have invented new and useful Improvements in Junction Members for Steel Sheet-Piling, of which the following is a specification.

My invention relates to an integral rolled junction member adapted for use with metal sheet piling to make connection between two or more adjacent pile sections in case of corners and transverse or intersecting walls.

This peculiar member may be easily rolled, complete in one piece, from the steel bloom, and consists of two or more interlocking elements radiating from a common center and arranged as near together as possible consistent with sufficient space for the coöoperating elements on the adjacent pile sections. As the said interlocking elements are set close together, without the interposition of a sustaining and separating web, the member in question is light in weight, simple and economical to manufacture, convenient to transport and to handle, and convenient and economical to drive. While it is perhaps not quite so rigid under the pile driver as wider members having webs, yet the radiating elements act as stiffening flanges, and my type of junction member is very rigid and sufficiently rigid for all practical purposes. Where special stiffness for hard driving is desired, the junction member may be assembled with one of the adjacent pile sections before driving. As said member is light and economical, it is particularly adapted for lighter work where the expense of heavier members, either roller integral or fabricated, would make them prohibitive.

My invention will be understood by reference to the drawing herewith in which the reference letters and numerals of this specification are used to indicate the corresponding parts in all the figures.

Figure 1 is an isometric view showing my interlocking member of four way construction used to connect an intersecting wall of steel sheet piling of the "Lackawanna" type to a main wall. The other figures show in plan various forms of my invention. Fig. 2 shows the same form of member as in Fig. 1 with four radiating

walls indicated. Fig. 3 shows a three-way member, and Fig. 4, a two-way member or corner piece. Fig. 5 shows a slight modification in the form of the member of Fig. 4. In all the foregoing figures the junction piece is formed to be used with "Lackawanna" piling but I do not wish to be limited thereto, for it may be shaped for use with various other standard types of piling. For instance in Figs. 6 and 7 junction pieces are shown adapted to the well known "United States" piling, being respectively a corner piece and a four-way member. In Fig. 7 as in Fig. 3, the interlocking elements are shown, cut away, leaving a space or pocket at the point of interlock to promote easy driving, to permit the introduction, or entrance, of filling material etc.

In the figures A indicates the junction member and B the usual pile sections to be connected thereby. Such pile sections are made as indicated of various forms and consist of a web and of interlocking elements along the web edges.

Little further description is necessary, in addition to the drawing and what has heretofore been said, fully to understand my invention.

Each junction member consists of at least two interlocking elements indicated by 1, radiating from a common center 2. There may be as many as desired, and I have shown three or four, which is probably the limit, for it would be neither practical, nor desirable, to provide the member with more elements than four. Each interlocking element operates as a stiffening flange to render more rigid the entire member.

In Fig. 4 there is interposed, between the two interlocking members 1, 1, a peculiar flange 3 which engages with the exterior of the hooks on the pile sections to brace them and render the joint more firm and rigid. A similar, but smaller, flange 4 is shown in Fig. 6.

In most of the figures, the interlocking elements on the junction member are shown substantially filling the pockets of the adjacent pile sections, but in many cases it will be desirable to form said elements as shown in Figs. 3 and 7 to leave the pockets 5 above mentioned.

In Figs. 5 and 6 I have shown the corner

100

95

105

piece provided with the shoulder 6 which stiffens the member and makes the joint more firm. These corner pieces are particularly simple and easy to roll.

5. In all the forms except that of Fig. 3, the interlocking elements extend substantially at 90° to each other.

It will be understood that what I here describe as my invention is a junction piece 10 having interlocking elements set adjacent and radiating from a common center, without superfluous metal, and preferably this piece is rolled integral, but it may be otherwise made, even fabricated if desirable, and 15 the interlocking elements may be of any desirable form, complementary to the elements on the adjacent piling with which they engage.

Having described my invention, I claim, 20 1. An integral, corner junction piece for interlocking metal piling having two interlocking elements connected to each other and arranged at an angle of about 90°.

2. An integral, rolled, corner, junction 25 piece for interlocking metal piling having two interlocking elements arranged adjacent and radiating from a common center at an angle of about 90° to each other.

3. A corner junction piece for interlocking, metal piling, having in combination two ball-like interlocking elements arranged at 30 an acute angle to each other to engage with socket-like elements on adjacent pile sections, and an integral flange extending outwardly in said angle to engage with the exterior of the socket-like elements.

4. An integral rolled corner junction piece 35 for interlocking metal piling, having in combination two ball-like interlocking elements arranged adjacent and at an acute angle to each other to engage with socket-like elements on adjacent pile sections, a flange outwardly extending in said angle to 40 engage with the exterior surface of said socket-like elements and a stiffening member opposite the flange, substantially as described and shown.

5. A webless interlocking pile section 45 forming a junction member between adjacent sections, comprising a plurality of in-

terlocking elements set adjacent to each other and radiating from a common center.

6. An integral webless interlocking pile section forming a junction member between adjacent sections, comprising a plurality of 55 interlocking elements set adjacent to each other and radiating from a common center.

7. An interlocking pile section to be used as a junction member between interlocking metal sections and comprising at least three 60 interlocking elements set adjacent to each other and radiating from a common center, said elements extending equal distances from the center and uniformly spaced with reference to each other.

8. An integral rolled steel pile section to be used as a junction member between interlocking metal sections and comprising at least three 65 interlocking elements set adjacent to each other and radiating from a common center, said elements extending equal distances from the center and uniformly spaced with reference to each other.

9. A junction member for interlocking metal piling consisting of a plurality of 70 interlocking elements radiating from a common center, all said elements being of equal lengths.

10. An integral rolled junction piece for interlocking metal piling consisting of a plurality of ball-like interlocking elements set adjacent and adapted each to engage with a corresponding socket-like element on an adjacent pile section, all of said elements being of equal lengths and extending equal 80 distances from the common center.

11. A webless interlocking pile section forming a junction member between adjacent sections, comprising a plurality of interlocking ball-like elements set adjacent to 85 each other and radiating from a common center.

In testimony whereof I have signed my name to this specification in the presence of two subscribing witnesses.

WALTER E. BUCKINGHAM.
